US0D1053755S

(12) United States Design Patent (10) Patent No.: US D1,053,755 S
(45) Date of Patent: * Dec. 10, 2024

(54) BUCKLE

(71) Applicant: Birkenstock IP GmbH, Linz am Rhein (DE)

(72) Inventor: Giuseppe Altovino, Cologne (DE)

(73) Assignee: BIRKENSTOCK IP GMBH, Linz am Rhein (DE)

() Term: 15 Years

(21) Appl. No.: 29/896,523

(22) Filed: Jul. 5, 2023

Related U.S. Application Data

(62) Division of application No. 35/515,518, filed on Oct. 10, 2022 (U.S. filing date under 35 U.S.C. 384), and having an international filing date of Oct. 10, 2022, now Pat. No. Des. 1,011,004.
